DESIGN FOR WRITING PAPER OR SIMILAR MATERIAL

Sidney E. Deutsch and Norman D. Schneider,
New York, N. Y.

Application October 24, 1934, Serial No. 53,742

Term of patent 7 years

To all whom it may concern:

Be it known that we, Sidney E. Deutsch and Norman D. Schneider, citizens of the United States, residing in the city of New York, State of New York, have invented a new, original, and ornamental Design for Writing Paper or Similar Material, of which the following is a specification, reference being had to the accompanying drawing, forming part thereof.

The figure is a plan view of writing paper or similar material, showing our new design.

The portion of the drawing included between the intersections of lines AB, CD, EF and GH, represents the design unit, which unit is repeated

in regular succession, as indicated by the extensions beyond the unit boundaries.

The essential feature of the design comprises a multiplicity of pennant-like figures promiscuously disposed throughout the surface of the paper and of such subdued character relative to the paper background as to allow legible writing thereon.

We claim:

The ornamental design for writing paper or similar material, as shown and described.
